**BOWLING PIN IMPACT CURTAIN WITH
DISPLACEABLE FORWARD EDGE**

Ernest T. Witzke, Box 228, Rte. 3,

Lake Geneva, Wis. 53147

Filed Sept. 8, 1966, Ser. No. 577,860

10 Claims. (Cl. 273—53)

This invention relates to a bowling apparatus, and more particularly to a mechanism for operating a pin deflecting curtain attached to the frame of an automatic pin setting machine.

In the conventional automatic pin setting machine, a pit cushion or trigger board is suspended across the pit to stop the forward motion of the ball after the ball passes the end of the alley. The impact of the ball striking the cushion provides an impulse to start the pin setting cycle and raise the cushion and permit the ball to roll back into the rear portion of the pit, where a ball elevator lifts the ball and elevates it to the ball return. In most pin setting machines a heavy flexible curtain extends upwardly and forwardly from the cushion between the kickbacks and serves to deflect pins struck by the ball downwardly into the pit. In the conventional machine, the curtain is formed of relatively thick rubber or plastic and the forward end of the curtain is attached to a rod suspended from the kickbacks, while the rear end of the curtain is secured around a heavy rod provided with end pins which are removably engaged with sockets formed in the frame of the machine.

Occasionally during bowling a pin will fall forwardly on the alley or in the gutters to a location where the pin setting machine will not be able to gather the pin into the pit. In this situation the operator must reach through the pin setting machine and engage the neck of the pin with the forked stick and pull the pin back into the pit. In order to reach through the machine, it is necessary, when using the conventional curtain construction, for the operator to disengage the locking pins at the rear end of the curtain and lift the heavy curtain and hold it with one hand while engaging the raised end of the curtain with a hook in order to maintain the curtain in the raised position. After lifting and hooking the curtain, the operator then must lean beneath the raised curtain and retrieve the pin. After retrieving the pin, the curtain is then disengaged from the hook and the locking pins reengaged with the frame. This operation of lifting the heavy curtain and hooking it in the raised position and returning the curtain to its original position is a very difficult and time consuming operation.

The present invention is directed to a novel mechanism for raising and lowering the pin-deflecting curtain of an automatic pin setting machine. According to the invention, the curtain extends upwardly and forwardly from the pit cushion and the lower or rear end of the curtain is connected to a transverse support bar which is fixed to the frame of the pin setting machine. The upper or forward end of the curtain is connected to a transverse support bar and the ends of the support bar are attached to guide rods which extend forwardly through guide members along the sides of the frame of the machine. The forward ends of the guide rods are connected to springs, and the force of the springs acts against the weight of the curtain to provide a counterbalancing force. When the operator desires to reach in through the machine to retrieve a pin, he merely pulls down on the upper or forward end of the curtain which moves the forward end of the curtain down to a position parallel to and adjacent the rear end of the curtain. Due to the counterbalancing force of the springs, the curtain can be moved with very little force and will be retained in any given position throughout its path of movement.

2

To enable the forward end of the curtain to move down to a parallel location to the rear end, the guide rods are formed with a downwardly convex shape and are provided with bends which engage locking hooks on the frame to thereby lock the curtain in the downward position.

As it is not necessary to disengage or unlock the curtain in order to move it to its lower or rear position, as is required in the conventional machine, the time spent in retrieving a pin is substantially reduced.

As a further advantage, the device of the invention provides greater access for the operator to retrieve pins and increases the visibility to the alley. In the conventional machine in which the curtain is lifted and locked in a raised position, the operator must bend down and lean beneath the raised curtain to retrieve the pin. Not only is there limited access beneath the curtain but visibility is greatly restricted. However, with the present invention the forward or upward end of the curtain is pulled downwardly and to the rear so that the operator can reach over the curtain, thus providing greater visibility and access to the alley.

In the past, the unlocking and raising of the curtain in the conventional pin setting machine frequently triggered the pin setting mechanism with the result that the operator would have to back out of the way until the pin setting cycle was completed. With the present invention the curtain is merely pulled down and no disengagement is necessary, making it virtually impossible to accidentally trigger the pin setting mechanism.

Other objects and advantages will appear in the course of the following description.

The drawings illustrate the best mode presently contemplated of carrying out the invention.

In the drawings:

FIGURE 1 is a perspective view of a portion of the frame of a conventional automatic pin setting machine incorporating the invention;

FIG. 2 is a longitudinal section showing the curtain-operating mechanism with the curtain being in the normal operating position;

FIG. 3 is a view similar to FIG. 2 showing the curtain in the lowered or pin-retrieving position; and

FIG. 4 is a fragmentary plan view of the curtain and operating mechanism.

The drawings illustrate a bowling alley 1 having a gutter 2 along each side edge. The alley 1 and gutters 2 terminate in a pit 3 and a pair of kickbacks 4 are located along the sides of the pit 3 and carry or support the frame 5 of the pin setting mechanism. The frame 5 is of conventional construction and in itself forms no part of the invention. For purposes of clarity in the drawings, only a portion of the frame is shown.

A trigger board or pit cushion 6 is located transversely across the pit 3 at a location slightly above the bottom surface of the pit. Pit cushion 6 is supported by a pair of support arms 7 which extend upwardly and are connected to triangular plates 8. Plates 8 are connected by straps 9 to a cross beam 10 of frame 5 which extends transversely across the pit.

Frame 5 also includes a pair of vertical beams 11 which are secured to cross beam 10 and a horizontal arm 12 connects the lower end of each vertical beam 11 and the respective support arm 7.

According to the invention a heavy curtain 13 made of rubber, plastic, leather or the like, extends upwardly and forwardly from the cushion 6 and serves to deflect any pins propelled by the bowling ball downwardly into the pit. The lower or rear end of curtain 13 is secured to a generally horizontal rod 14 and studs 15 extend outwardly from the ends of the rod 14 and are secured within suitable openings in the support arms 7. Similarly, the

forward end of the curtain 13 is secured around a horizontal rod 16, and the ends of rod 16 are connected to generally curved guide rods 17 which extend longitudinally of the alley along the sides of the frame 5. As shown in FIG. 4, the ends of the guide rods 17 extend through openings in the forward rod 16 and are engaged by nuts 18.

Each of the guide rods 17 is guided for movement within an opening 19 in a guide bracket 20 which extends laterally inward from each horizontal arm 12 of frame 5. The outer portion of each of the guide rods 17 is formed with a bend 21 and the end of the rod is bent downwardly as indicated by 22.

The guide rods 17 which support the upper or forward end of the curtain 13 are urged forwardly by coil springs 23. The rear end of each spring 23 carries a hook 24 which is engaged with the end 22 of the respective guide rod 17, while the outer or forward end of each spring 23 carries a hook 25 which is engaged with vertical frame member 26. With this arrangement the springs 23 act to move the rods 17 forwardly and thereby serve as a counterbalancing force against the weight of the curtain 13. The engagement of the guide rods 17 with the openings 19 in guide brackets 20 provides a certain degree of frictional resistance which, in combination with the counterbalancing effect of the springs 23, serves to maintain the curtain in any desired position.

During normal operation of the pin setting machine, the curtain is in the position shown in FIG. 2 and extends upwardly and forwardly from the cushion 6. As previously mentioned, the curtain will be held in this position by the counterbalancing force of the spring 23 and the frictional engagement of the rods 17 within the openings in guide brackets 20.

In the event the operator wishes to reach through the pin setting machine to retrieve a pin, he merely grasps the forward rod 16 and pulls the curtain 13 downwardly and rearwardly. The downwardly convex curvature of rods 17 enables the forward rod 16 to be moved to a position where the rod 16 is adjacent and parallel to the rod 14, as shown in FIG. 3. The curtain will be maintained at any position due to the counterbalancing effect of the springs 23.

To lock the curtain 13 in the downward position, the bends 21 in the rods 17 engage wire hooks 27 attached to the brackets 19 to provide a frictional locking engagement.

Due to the counterbalancing effect, the curtain can be raised and lowered with very little force. Moreover, it is not necessary to disengage any locking mechanism to raise or lower the curtain, for the curtain can be moved by merely pulling downwardly or pushing upwardly on the forward rod 16. This greatly simplifies the operation of moving the curtain to a position where access can be had to the alley and therefore greatly speeds up the time required to retrieve a pin from the alley or gutter.

The mechanism of the invention also provides greater access and visibility to the alley and gutter. As the forward end of the curtain is pulled downwardly to a position adjacent the lower end, as shown in FIG. 3, the operator can merely lean over the curtain to retrieve a pin. This differs from the conventional curtain structure in which the operator is required to bend underneath the lifted curtain when attempting to retrieve a pin.

Various modes of carrying out the invention are contemplated as being within the scope of the following claims particularly pointing out and distinctly claiming the subject matter which is regarded as the invention.

I claim:

1. In a bowling apparatus, comprising an alley, a pit located at the rear of the alley, a frame mounted above the pit, a cushion carried by the frame and extending transversely of the pit and positioned to be engaged by a

bowling ball, a curtain carried by the frame and having one end fixed to the frame and located adjacent the cushion and having the opposite end disposed forwardly and upwardly of said cushion, movable support means connected to said opposite end of the curtain, and counterbalancing means connected to the opposite end of the curtain for counterbalancing the weight of the curtain, said opposite end being movable from a first pin deflecting position, whereat said opposite end is a substantial distance from said first end, to a second position whereat said opposite end is located generally parallel and adjacent to said first end.

2. The apparatus of claim 1 in which said movable support means comprises a guide rod with the inner end of said guide rod being connected to said opposite end of the curtain, and guide means connected to the frame for supporting the rod in movement.

3. The apparatus of claim 2 in which said counterbalancing means is connected to the outer end of the guide rod.

4. The apparatus of claim 3 in which said counterbalancing means is a resilient member.

5. The apparatus of claim 2 in which the guide rod extends generally longitudinally of the alley and at least a portion of the guide rod has a downwardly convex contour.

6. The apparatus of claim 2 and including means connected to the guide rod for locking the guide rod with respect to the frame.

7. In a bowling apparatus, an alley, a pit located at the rear of the alley, a frame mounted above the pit, a cushion carried by the frame and extending transversely of the pit in a position to be engaged by a bowling ball, a flexible curtain having a first end fixed to the frame and located adjacent the cushion and having a second end disposed forwardly and upwardly of said cushion, a plurality of guide members extending longitudinally of the alley and connected to said second end of the curtain, guide means carried by the frame for mounting said guide members for movement relative to the frame and longitudinally of the alley, and counterbalancing means connected to said guide members for counterbalancing the weight of said second end of the curtain.

8. The apparatus of claim 7, and including a first support member extending transversely of the pit and secured to said first end of the curtain and a second support member extending transversely of the pit and attached to the second end of the curtain, said guide members being connected to said second support member, said second support member being movable from a first position, whereat said second support member is located a substantial distance from said first support member, to a second position whereat said second support member is located parallel and adjacent to said first support member.

9. The apparatus of claim 7, in which at least one of said guide members is provided with an abutment and said apparatus includes means connected to the frame and engageable with said abutment to lock the guide member at a given position.

10. The apparatus of claim 7, in which the counterbalancing means comprises a coil spring connected between the frame and the guide members.
